DISPLAY CONTAINER FOR A PERFUME BOTTLE OR THE LIKE

William W. Hobé, New York, N. Y.

Application June 18, 1951, Serial No. 15,594

Term of patent 3½ years

(Cl. D80—5)

To all whom it may concern:

Be it known that I, William W. Hobé, a citizen of the United States of America, residing in New York city, county of New York, and State of New York, have invented a new, original, and ornamental Design for a Display Container for a Perfume Bottle or the Like, of which the following is a specification, reference being had to the accompanying drawing, forming part thereof, wherein,

The rear and side of the design are identical to that shown in Figs. 1 and 2, except for the omission of the square shaped latch.

I claim:

The ornamental design for a display container for a perfume bottle or the like, substantially as shown and described.

WILLIAM W. HOBÉ.
